UNITED STATES PATENT OFFICE

FAY D. KINNEY, OF WENHAM, MASSACHUSETTS, ASSIGNOR TO UNITED SHOE MACHINERY CORPORATION, OF PATERSON, NEW JERSEY, A CORPORATION OF NEW JERSEY

SHOE CEMENTING

Application filed January 12, 1928. Serial No. 246,304.

This invention relates to machines for and methods of applying cement to shoes and is herein exemplified with particular reference to applying cement to the foxing areas of tennis shoes.

In the manufacture of canvas shoes having rubber soles and of the type called "tennis" shoes, it is the usual practice to secure a thin strip of unvulcanized gum rubber, termed a foxing, around the periphery of the bottom of the lasted shoe prior to the application of the rubber sole. This strip has been secured in place by means of a heavy, viscous cement which commonly is applied by hand, the operator holding a brush filled with the cement in one hand while presenting the shoe thereto with the other hand and turning the shoe so as to present all portions of the area to which the foxing is to be applied to the brush. The foxing is then applied to the cement coated foxing area after which the rubber sole is cemented to the shoe with its edge overlapping the foxing strip, and the sole and foxing are vulcanized together.

The proper appearance of the completed shoe depends largely upon the proper positioning of the foxing strip on the shoe, the aim being to locate the strip so that all points in its upper edge are at a uniform distance, approximately a half inch, from the bottom of the shoe. Furthermore, in order to produce a commercially satisfactory product, it is necessary for the stripe of cement to coincide at its upper edge accurately with the upper edge of the foxing strip. In other words, if the cement shows above the foxing strip, the appearance is unsatisfactory and if the foxing strip overlaps the stripe of cement, then the edge of the strip is not properly secured to the shoe and the appearance not only is not satisfactory but there is danger of accidental tearing away of the strip. On the other hand, in spite of these requirements, experienced operators have acquired a skill such that the speed of their work is very considerable.

One object of the present invention is to provide a machine for applying cement to the foxing areas of shoes which will produce work at a speed at least as great as the

speed obtained by hand work and of more uniformly satisfactory quality.

To this end, and in accordance with a feature of the invention, the illustrated machine, which is substantially automatic in its operation, is provided with an endless carrier having a series of shielding shoe supports adapted to receive and to protect portions of a plurality of shoes and to transfer the shoes successively past cement-applying mechanism, the shoes being thereafter removed in turn from the carrier. Preferably, and as herein illustrated, the machine is also provided with a drying chamber through which the coated shoes are passed in turn to dry the coating sufficiently so that the shoes may be readily removed from the carrier.

As has already been brought out, the accurate definition of the upper edge of the coated foxing area is important to the production of satisfactory work and in accordance with another feature of the invention, the illustrated shielding devices above referred to are constructed and arranged to protect the uppers of the shoes above the foxing areas from the application of cement while accurately defining the upper limits of the foxing areas. The shields may be in the form of plates having shoe-receiving openings corresponding in outline to the shapes of the bottoms of shoes to be cemented, the edges of said openings being curved vertically according to the vertical curves of the shoe bottoms in order that the foxing areas defined by the shields will be uniform in width around the shoes. In order to define accurately the upper edges of the foxing areas in shoes of different sizes, work-supporting shields having openings of different sizes are preferably provided, the illustrated work-supporting shields being detachably secured to the endless carrier so that they may be readily removed and replaced when desired.

Still another object of the invention is to provide improved cement-applying means by which all forms of cement may be readily projected in a spray on parts of boots and shoes.

It will be understood that the construction

of an apparatus which will be adapted to handle not only cement of medium body but will be equally capable of spraying the heavy and viscous types of cement, which usually have been employed for the foxing areas of shoes, is attended with difficulty. Furthermore, the situation is rendered even more complex when employing cement compounded of water-dispersed latex, which will 5 hereinafter be termed simply "latex", because of the fact that, while latex is thin enough for dispersion in the form of a spray without great difficulty when the machine is first started, this action cannot be continued 10 indefinitely because of the coagulation which is set up whenever the latex is subjected to pressure or friction by the handling apparatus. In accordance with still another feature of the invention, the illustrated machine 15 is provided with novel cement-spraying mechanism which utilizes the centrifugal force set up by a rotating applying device to which the cement is delivered to break up the cement into a spray for application to 20 a shoe part supported in the range of the spray produced by said applying apparatus. Because of the viscosity of certain types of cement, it is found desirable to make provision for restricting the delivery of cement 25 by the cement-applying device, and in the illustrated apparatus a rotary cement-projecting member having a restricted delivery slit adjacent to its periphery is provided, the cement being supplied to said rotary 30 member for delivery through said slit by the action of centrifugal force to break into a spray before it strikes the work. Also as illustrated, a flat disk is mounted for rotation about an upright axis positioned along 35 40 side of the shoe supports on which are carried the shielded shoes. Cooperating with this disk is a funnel-shaped annular member overlapping the surface of the disk and having one of its edges adjacent to but spaced 45 from the edge of the disk. This annular member cooperates with the disk to provide a restricted space in which cement is received for delivery and an annular peripheral slit through which cement is projected. 50 In order to increase the disperser of the spray, the disk is tilted with respect to its axis of rotation. Preferably, a plurality of disk cement-applying devices are provided, the cement-applying devices being located 55 upon opposite sides of the work support so that, as a shoe is carried progressively past the cement-applying devices, the two sides of the shoe are coated simultaneously step by step. Preferably too, a receptacle is provided 60 for catching surplus cement, and means is provided for returning the surplus cement to the spraying devices for reuse. 65 In its method aspect, the invention provides an improved method of spraying cement on the foxing area of a shoe, the upper

portion of which is surrounded by a shield to prevent the application of cement thereto, which is characterized by causing a relative movement of translation between a spraying device and the shielded shoe to present 70 different portions of the foxing area to the spraying device. As herein exemplified, the method comprises placing a shoe in operative relation to a shielding device to protect the portion of the upper lying above the foxing area and spraying cement on successive portions of the foxing area until the whole of the foxing area is coated. 75

In the drawings,

Fig. 1 is a side elevation of a foxing cementing machine embodying the invention in the machine aspect and adapted to be used in the practice of the method of the present invention, certain details being omitted for the sake of clearness; 80

Fig. 2 is an angular view, partly in section, through the cement-projecting disks and the associated tank, and illustrating a work-support and shielding device with a shoe supported therein; 90

Fig. 3 is a transverse vertical section through the machine adjacent to the cement-applying apparatus;

Fig. 4 is a fragmentary diagrammatic plan view showing part of a work-support with a 95 shoe therein and an adjacent cement-applying disk;

Fig. 5 is a fragmentary sectional view through the shoe and a portion of the adjacent shielding device together with one of 100 the cement-projecting disks, illustrating diagrammatically the dispersion of the spray thrown off by the disk.

In order that a plurality of shoes may be readily presented successively to the cementing and drying apparatus of the illustrated machine, there is provided a conveyor in the form of an endless carrier 10 passing over suitable wheels 12 and 14 journaled upon opposite ends of a supporting frame 16. This 105 endless carrier 10, as shown in Figs. 1 and 2, is made up of a series of parallel links 18 pivoted at their ends on the axes of grooved rollers 20. These rollers are received in correspondingly shaped recesses 22 in the end 110 wheels and rails 24 are provided along the upper run of the frame 16 which form tracks for the rollers and thereby support the carrier and the shoes thereon at a predetermined level. The axes of alternate rollers 20 also 115 serve pivotally to support side carriers 26 having inturned bottom flanges 28 at their lower edges and outturned lips 30 and 32 at the ends of their upper edges and resting on adjacent links when the carrier is traveling 120 along the rails 24. The inturned bottom flanges 28 of the side carriers 26 are provided with upstanding pins 34 to receive suitably perforated combined work-supports and shields 40 which are held detachably in posi- 130

tion upon the side carriers 26 by means of spring latches 42.

It will be assumed that the shoes to be treated have been arranged according to size 5 and the machine provided with work-supports 40 corresponding in size to the shoes to be presented to the machine. Each of the work-supports 40 comprises a plate or shield having a shoe-receiving opening 44 corresponding in outline to the outline of the bottom of a shoe, said shield being associated with the shoe itself and surrounding the shoe to protect the upper above the foxing area. The combined work supports and shields 40 have 15 cross-rods 48 and 50 extending across the opening 44 and upon which the bottom of the shoe rests and the edges of this plate at the opening are curved upwardly as at 46 (Fig. 2) with respect to the plane of the work-support 20 port so that, when a shoe is supported on the rods 48 and 50, the edge of the opening 44 will coincide with the upper edge of the foxing area of the shoe as it supports a shoe positioned therein. With this form of work-support 25 port, it is only necessary for the operator to deposit one shoe after another in the openings of the work-supports 40 at the left end of the machine, viewed as in Fig. 1, and to remove them from the work-supports at the right end 30 of the machine, the conveyor being effective automatically to present shoes to the applying devices and to remove them therefrom.

It will be understood that the openings 44 of the successive work-supports are shaped 35 alternately for right and for left shoes.

The application of cement to the shoes successively presented by means of the carrier 10 is effected by projecting the cement from a pair of rotary disks 52 and 54 arranged 40 upon opposite sides of the path of movement of the shoe and mounted in tilted position at the upper end of shafts 56 and 58 which are journalled in the frame 16 of the machine and in the bottom of a tank 60. 45 These rotary members 52 and 54 are driven at sufficient speed so that they disperse the cement in the form of a fine spray to all sides of the axis of each of them. By properly proportioning the speed of rotation to the 50 character and viscosity of the cement, the action of centrifugal force will cause the cement to be distributed in a fine film over the surface of the rotating cement applying device and this film will be broken up into a 55 fine spray by the resistance of the air as soon as it leaves the disk. The apparatus, therefore, facilitates the projection of cement in the form of a spray without any possibility of clogging the outlet opening of the cement 60 applying device. The cement which is not used is caught in the tank 60 which is preferably shaped so that the surplus cement will drain to an outlet pipe 62 from which it is 65 removed by means of a suitable pump (not shown) and delivered again, for reuse, to

the disks through supply pipes 64 and 66, each of which is provided with a control valve 68. The shafts 56 and 58 for the oppositely directed spraying devices are joined by means of a crossed driving belt 70 and power is supplied for rapid rotation of the disks by means of an electric motor 72, here shown as directly connected to the shaft 56. It will be observed from an inspection of Fig. 5 that additional dispersion of the spray in fan-shaped fashion above and below the plane of the center of rotation of the disks results from the tilted position of the disks upon their axes of rotation, this dispersion being sufficient to coat the whole vertical extent of 75 the foxing area, which is indicated in that figure by the blackened portion 74 extending around the corner of the shoe 76 as well as the bottom of the shoe.

In order that excessive quantities of cement may not be thrown from the surfaces of the rotating disks 52 and 54, coupled members or annular guards 80 mounted in overlapping relation to the disks are provided which cooperate with the disks to form restricted spaces provided with restricted outlet openings near the periphery of each disk through which the cement will be delivered. As herein shown the guards 80 are funnel-shaped hollow frusto-conical members which are mounted directly upon the disks themselves and held thereon by means of suitable supports 82 with their edges adjacent to but spaced from the edges of the disks to form a restricted annular delivery slit adjacent 100 to the periphery of the rotary disk. The restricted partially enclosed spaces provided between the guards 80 and the disks 52 and 54 have inlet openings 84 through which cement is supplied by means of pipes 64 and 66 for delivery through the peripheral openings of the rotary members.

The ends of the tank 60 are cut away as shown at 86 (Fig. 3) to provide a pathway above the cement in the tank along which 110 the successive shoes may pass, and covers 88 and 90 (Fig. 2) are provided which extend from the outer edges of the tank to the tracks 24 thereby partially to cover the tank outside of the pathway of the conveyor 10. It 115 will be noted that the space between the tracks is practically covered by the successive work-supports 40 associated therewith, thereby giving little opportunity for the scattering of the cement spray into the open air. 120 If desired, the movement of the endless carrier may be effected by means of power supplied from the same motor 72 and to this end, there is shown in Fig. 1 a worm and gear drive 92 for a counter shaft 94 journalled in the frame 16 which is connected by a sprocket and driving chains 96 and 98 to the end wheel 12.

It will be observed from an inspection of Fig. 4 that the rotating disks 52 and 54, 130

throwing a spray horizontally in all directions, are effective to coat both sides of the shoe simultaneously as the shoe moves along the pathway between said disks. The toe 5 end will be coated as the shoe approaches the disks, while the heel end will be coated as the shoe recedes from the disks and the upper edge of the coated area will be accurately defined by the co-action of the shields 10 40 with the shoes.

After the shoes are coated, they are carried through a drying chamber 100 provided with suitable heating means, such as stream 15 pipes 102 and having entrance and exit openings which are protected by flaps 104 and 106. By means of this arrangement, a sufficient proportion of the moisture or solvent in the cement is removed so that the shoes may be readily handled as they emerge from the drying 20 chamber and be removed by the operator by lifting them in turn as indicated by the arrow 110.

Having thus described my invention, what I claim as new and desire to secure by Letters Patent of the United States is:

1. In a machine for applying cement to the parts of boots and shoes, a rotary applying device having a restricted opening extending around its periphery, means for supplying cement to said rotary device for expulsion in a spray through said opening, and means for supporting a shoe part in the path of the spray of cement.

2. In a foxing cementing machine, a shoe 35 support, means for applying cement to the foxing area of a shoe carried on said shoe support comprising a rotary cement applying device having a partially enclosed chamber provided with a restricted delivery slit 40 adjacent to its greatest diameter and extending substantially around its periphery, means for rotating said member, and means for supplying cement to said device within said partially enclosed chamber.

3. In a foxing cementing machine, a shoe support, protecting and limiting means associated with said support in fixed relation thereto and constructed and arranged to expose only the foxing area of a shoe thereon 50 and to shield from the application of cement the upper portion of a shoe above its foxing area, means for applying cement to said foxing area comprising a rotary disks, means for rotating said disk, and means for supplying cement to one surface of the said disk for projection by centrifugal force directly 55 upon the exposed foxing area.

4. In a foxing cementing machine, a shoe support, means surrounding a shoe and secured to said support for protecting the portion of a shoe above the foxing area from the application of cement, a rotary cement applying device constructed and arranged to apply cement in a spray to the exposed fox- 65 ing area by the action of centrifugal force,

and means for collecting surplus cement delivered by the applying device.

5. In a foxing cementing machine, a shoe support, means secured to said support in predetermined relation thereto for protecting a portion of the shoe carried on said shoe support from the application of cement, a driven rotary cement applying device constructed and arranged to apply cement in a spray to a portion of the shoe not protected by said means, and means for collecting surplus cement and returning it to the rotary means for reuse.

6. In a foxing cementing machine, a shoe support, a disk rotatable about an axis at one side of said shoe support, an annular member associated with the disk, said member and said disk being relatively constructed and arranged to form between them a restricted space provided with a narrow peripheral outlet, and means for supplying cement to said restricted space for delivery through said outlet as said disk is rotated.

7. In a foxing cementing machine, a shoe support, cement applying means comprising a disk rotatable about an axis at one side of said shoe support, an annular member associated with said disk, said member and said disk being relatively constructed and arranged to form between them a restricted space provided with a narrow peripheral outlet, means for supplying cement to said applying means in said restricted space, and means for rotating said disk at a sufficient speed to cause the delivery of the cement through said outlet opening by centrifugal force.

8. In a foxing cementing machine, a shoe support, a cement applying device comprising a disk rotatable adjacent to said support, a cupped member cooperating with said disk to form a partially enclosed space adjacent to one side of the disk, said cupped member being spaced from the disk around the periphery of the latter, thereby to provide a narrow slit through which cement may be thrown by the centrifugal action of the disk, and means for supplying cement to said device for projection through said slit.

9. In a foxing cementing machine, a shoe support, a cement applying device comprising a disk rotatable about an upright axis at one side of said shoe support, and a frustoconical hollow member rotatable with said disk and supported upon the disk in spaced relation thereto to provide a peripheral slit, and means for supplying cement to said device for projection through said slit.

10. In a foxing cementing machine, a support for a shoe, a disk rotatable about an axis beside the shoe support, said disk being inclined to its axis of rotation, a guard mounted on said disk with its outer edge spaced from the adjacent surface of the disk, and means

for supplying cement to said surface of the disk within said guard.

11. In a foxing cementing machine, a support to hold a shoe in its normal upright position, a disk rotatable about an upright axis beside the shoe support, said disk being inclined to its axis of rotation, a guard, mounted on said disk with its outer edge spaced from the upper surface of the disk, and means for supplying cement to said surface of the disk within said guard.

12. In a foxing cementing machine, a disk rotatable about a vertical axis, said disk being inclined with respect to its axis of rotation, a frusto-conical guard secured to the upper surface of the disk with its lower edge spaced from the upper surface of the disk, said guard being provided with an inlet opening adjacent to the axis of rotation, and means for supplying cement to the upper surface of the disk through said inlet opening.

13. In a foxing cementing machine, a rotatable disk for applying cement to the foxing area of a shoe, and means for supplying cement to said disk to be thrown from its peripheral edge, said disk being constructed and arranged to provide a spray which is dispersed to cover an area above and below the plane of the center of rotation of the disk.

14. In a foxing cementing machine, a rotatable disk, means for supporting a shoe laterally of said disk, and means for supplying cement to the surface of said disk, said disk being constructed and arranged to deliver a fan-shaped spray to the whole vertical extent of the foxing area of the shoe.

15. In a foxing cementing machine, a disk rotatable about a vertical axis, means for supplying cement to the upper surface of said disk, said disk being tilted with respect to the axis of rotation so as to deliver a fan-shaped spray, sufficiently extended to coat simultaneously the whole vertical extent of the foxing area at any part of a shoe which is presented to the spray.

16. In a foxing cementing machine, a shoe support, an applying disk rotatable about an axis at one side of said shoe support and arranged to provide a dispersed spray, sufficiently extended simultaneously to coat the whole vertical extent of the foxing area at any part of a shoe on said shoe support which is exposed to the spray, means for supplying cement to one surface of the disk, and means for shielding a portion of a shoe on the support from coating with cement.

17. In a foxing cementing machine, a cement applying device, means for shielding completely the uppers of shoes above the foxing areas as said shoes are presented to said applying device whereby only the foxing areas of the uppers are coated with cement, and means for automatically removing shoes

which have been presented to the applying device.

18. In a foxing cementing machine, a cement applying device, shoe surrounding means for shielding the uppers of shoes above the foxing areas, whereby when presented to said applying device only the foxing area is coated with cement, and means for automatically presenting a series of shoes to the cement applying device.

19. In a foxing cementing machine, a cement-spraying device, and connected means for shielding the uppers of a plurality of shoes down to the upper edges of the foxing areas, and presenting successive shoes progressively to said spraying device to coat the unshielded foxing areas.

20. In a foxing cementing machine, a coating device for applying cement to the foxing areas of shoes, a conveyor for successively presenting a plurality of shoes to said coating device, and means on said conveyor for shielding portions of said shoes from the application of cement while leaving the foxing areas exposed for the action of the coating device.

21. In a foxing cementing machine, a conveyor provided with a series of supports for shoes, shields on said conveyor in predetermined relation to said supports and constructed and arranged to protect the uppers of shoes above their foxing areas and spraying devices arranged to coat the exposed foxing areas of the shoes on conveyor.

22. In a foxing cementing machine, a cement applying mechanism, and an endless carrier movable past said cement applying mechanism, said carrier being provided with a series of shielding shoe supports in which shoes may be inserted at one end of the carrier and transferred past the cement applying mechanism by the carrier to coat a portion of each shoe.

23. In a foxing cementing machine, a cement spraying device, means for shielding the upper portion of a shoe to protect said portion from the application of cement, and means for causing a relative movement of translation between said cement spraying device and the shielded shoe to present successive portions of the foxing area to the spraying device.

24. In a foxing cementing machine, a conveyor, oppositely directed cement spraying devices arranged upon opposite sides of said conveyor, and means for supporting partially shielded shoes upon said conveyor for movement between the oppositely directed sprays of cement provided by said spraying devices thereby to coat the unprotected portion of the shoe.

25. In a foxing cementing machine, a conveyor, means for supporting shoes on said conveyor constructed and arranged to shield the shoes above their foxing areas, and cen-

- trifugal cement-applying devices arranged upon opposite sides of the conveyor and constructed and arranged to coat the whole of the foxing areas of the shoes on the conveyor as they are successively carried past said cement-applying devices by said conveyor.
26. In a foxing cementing machine, a conveyor, means for supporting shoes on said conveyor constructed and arranged to shield the shoes above their foxing areas, and cement applying devices arranged upon opposite sides of the conveyor and constructed and arranged to coat the whole of the foxing areas of the shoes on the conveyor as they are successively carried past said cement applying devices by said conveyor.
27. In a foxing cementing machine, a conveyor, means for supporting shoes on said conveyor constructed and arranged to shield the shoes above their foxing areas and cement spraying devices arranged upon opposite sides of the conveyor and constructed and arranged to coat the whole of the foxing areas of the shoes on the conveyor as they are successively carried past said cement spraying devices by said conveyor.
28. In a foxing cementing machine, a conveyor for a series of shoes provided with shoe shielding means, and cement applying means for coating the foxing areas of shoes on said conveyor, said shielding and said applying means being constructed and arranged accurately to define the upper edges of the foxing areas.
29. In a foxing cementing machine, a conveyor for shoes, shoe shielding and cement applying means for coating the foxing areas of shoes on said conveyor constructed and arranged accurately to define the upper edges of the foxing areas, and drying means associated with said conveyor.
30. In a foxing cementing machine, a partially covered cement tank having a pathway extending thereacross above the cement in the tank, shoe conveying means extending along said pathway, a spraying device arranged within the tank laterally of the pathway for coating the foxing area of a shoe on said conveying means, and a shoe supporting means carried by said conveying means and arranged to protect a shoe from the application of cement above the foxing area.
31. In a foxing cementing machine, a partially covered cement tank having a pathway extending thereacross above the cement in the tank, shoe conveying means extending along said pathway, a spraying device arranged within the tank laterally of the pathway for coating the foxing area of a shoe on said conveying means, shoe supporting means carried by said conveying means and arranged to protect a shoe from the application of cement above the foxing area, and means for removing surplus cement from the tank and delivering it to the spraying device.
32. In a foxing cementing machine, cement applying mechanism, and an endless shoe carrier associated therewith and movable in a definite path in relation to said applying mechanism, said carrier being provided with a series of detachable shoe supports having shielding devices combined therewith by means of which the uppers of the shoes above the foxing areas are protected from the application of cement while the foxing areas are left exposed for the application of cement as the carrier transfers the shoes past the cement applying mechanism.
33. In a foxing cementing machine, cement-applying mechanism, and a conveyor constructed and arranged to carry each of a succession of shoes in turn progressively past the cement-applying mechanism, said carrier being adapted to receive interchangeably any one of a plurality of series of shoe supports and each of said series comprising a plurality of shoe supports adapted to receive and position shoes of a given size or shape.
34. In a foxing cementing machine, cement applying mechanism and a conveyor constructed and arranged to carry each of a succession of shoes in turn progressively past the cement applying mechanism, said carrier being adapted to receive interchangeably any one of a plurality of a series of shoe supports, and each of said series comprising a plurality of shoe supports having shoe receiving openings and adapted to protect a portion of a shoe above its foxing area from the application of cement, said shoe supports being adapted to receive and position shoes of a given size or shape.
35. In a foxing cementing machine, a covered cement tank provided with a pathway extending thereacross above cement in the tank, means for conveying a shoe along said pathway, upright shafts journaled on opposite sides of said pathway, centrifugal spraying devices on said shafts within the tank, and means for removing surplus cement from the tank and delivering it to said centrifugal spraying devices.
36. In a foxing cementing machine, a cement-spraying device, movable means for presenting a shoe to said spraying device including a removable shield having an opening to receive a shoe, said shield being shaped closely to approach the upper edge of the foxing area of the shoe, and means for supporting a shoe within the opening of said shield with said foxing area exposed.
37. In a foxing cementing machine, a partially closed cement tank provided with an opening, applying devices on opposite sides of said tank constructed and arranged to coat the foxing area of a shoe as it passes over the tank, and a traveling shoe support arranged to pass said opening and con-

structed and arranged to shield the portion of a shoe above the foxing area from the application of cement.

38. In a foxing cementing machine, a partially closed cement tank provided with an opening, applying devices on opposite sides of said tank constructed and arranged to coat the foxing area of a shoe as it passes over the tank, a traveling shoe support arranged to pass said opening and constructed and arranged to shield the portion of a shoe above the foxing area from the application of cement, and means for removing surplus cement from the tank and delivering it to said applying devices.

39. In a foxing cementing machine, a partially covered cement tank, an associated shoe shielding device having a shoe-bottom shaped opening to admit the bottom portion of a shoe and adapted to surround a shoe to protect the upper portion of the shoe above its foxing area from the application of cement, whereby a shoe may be projected through the opening in the shielding device into position in the tank to expose its foxing area beneath the shielding device, and cement applying devices within said tank and disposed upon opposite sides of the shoe.

40. In a foxing cementing machine, a partially covered cement tank, an associated shoe shielding device having an opening to admit the bottom portion of a shoe and adapted to surround and thereby protect the upper portion of a shoe above its foxing area from the application of cement, whereby a shoe may be projected through the opening in the shielding device into position in the tank to expose its foxing area beneath the shielding device, and centrifugal spraying devices within said tank and disposed upon opposite sides of the shoe arranged to project the cement upon the unprotected bottom portion of the shoe.

41. In a foxing cementing machine, a partially covered cement tank, an associated shoe shielding device having a shoe-bottom shaped opening to admit the bottom portion of a shoe and adapted to surround a shoe to protect the upper portion of the shoe above its foxing area from the application of cement, whereby a shoe may be projected through the opening in the shielding device into position in the tank to expose its foxing area beneath the shielding device, cement applying devices within said tank and disposed upon opposite sides of the shoe, arranged to coat the unprotected bottom portion of the shoe, and means for receiving surplus cement from the tank and redelivering it to said cement applying devices.

42. That method of applying cement to the foxing area of a shoe, the whole upper portion of which above the foxing area is surrounded by a shield to prevent the application of cement thereto, which is characterized by causing a relative movement of trans-

lation between a spraying device and the shielded shoe, with the shoe held bottom facing downwardly, to present successive portions of the foxing area to the applying device.

70

43. That method of applying cement to the foxing area of a shoe, the whole upper portion of said shoe being shielded at the same time to prevent the application of cement thereto which is characterized by holding said shoe with its bottom facing downwardly, causing a relative movement of translation between a spray and the shielded shoe to coat the whole vertical extent of each successive portion of the foxing area at any part of the shoe which is brought into the spray without danger that the cement will run over the shielded portion.

75

44. That method of applying cement to the foxing area of a shoe which consists in surrounding the whole upper portion of the shoe by a shield to prevent the application of cement thereto, and moving the shielded shoe between sprays of cement directed in opposite directions against the sides of the foxing area of the shoe.

80

45. That method of applying cement to the foxing area of a shoe which consists in passing the bottom of a shoe through the opening of an apertured shielding device whereby the shield will protect the portion of the upper lying above the foxing area, and causing relative movement of translation between the protected shoe and a plurality of cement sprays to coat the whole of the unshielded foxing area.

95

46. That method of applying cement to the foxing area of a shoe which consists in holding a shoe right side up, protecting the portion of the upper lying above the foxing area by surrounding it with a shield, positioning said protected shoe in operative relation to a cement spray and causing relative movement of the shoe and the spray to coat the whole of the unshielded foxing area.

100

In testimony whereof I have signed my name to this specification.

FAY D. KINNEY.

110
